WATER GAS PROCESS

Harry Brownley Pearson, Jr., New York, N. Y., assignor to Semet-Solvay Engineering Corporation, New York, N. Y., a corporation of New York

Application July 19, 1938, Serial No. 219,974

5 Claims. (Cl. 48—208)

This invention relates to processes for making carburetted water gas and more particularly to a novel process for minimizing explosion hazards in water gas operation.

5 Within the past few years the carburetted water gas industry has adopted a novel type of water gas set involving a generator, carburetor and superheater located in separate and detached shells and connected in series, the top of the 10 generator communicating with the base of the carburetor, and the top of the carburetor communicating with the top of the superheater so that flow takes place up through the carburetor and down through the superheater, just the reverse of the direction of flow in conventional carburetted water gas equipment. This novel water 15 gas set is disclosed and claimed in United States Patent No. 2,118,096, granted May 24, 1938, and will be hereinafter referred to as the "Reverse flow water gas set." In the operation of such 20 reverse flow water gas sets it was found that during the starting up periods pops or explosions would occur, particularly within the carburetor and at times in the superheater. Such pops or 25 explosions are objectionable, not only because they have a deleterious effect upon the refractory lining and brickwork within the carburetor and superheater, but also they indicate that explosive mixtures of gas are formed within the 30 set during the starting-up period which upon ignition might cause an explosion of sufficient intensity to destroy the water gas set. The problem of preventing the formation of such explosive mixtures within the set has received the attention 35 of gas engineers, but, to my knowledge, no satisfactory solution thereof has been found prior to my invention.

I have discovered the occurrence of explosions in the water gas set while introducing fuel into the generator and during the starting-up period 40 is caused by the tendency of the gases evolved in the generator upon charging to rise through the open fuel charging inlet and create a back-draft through the carburetor, superheater and stack, thus causing air to be drawn through the stack valve and form explosive mixtures in the set; the mixtures explode when they are raised to 45 ignition temperature by the hot refractory material in the set. The tendency of the hot gases evolved in the generator during charging to cause the entry of air into the set through the stack valve in the reverse flow set, I believe, is augmented by the draft exerted by the downflow superheater on the open stack valve, i. e. the natural 50 tendency of hot gas to rise within the super-

heater exerts a draft on the open stack valve, particularly if the valve is placed in a stack of a height not substantially greater than that of the superheater, and causes air to enter through the open stack valve in an amount sufficient to form an explosive mixture with the combustible gas present in the set.

I have found that the formation of such explosive mixtures may be prevented in the operation of such reverse flow sets during the starting-up period by causing a jet of suitable gas, preferably steam, to flow upwardly through the stack concurrently with the opening of the charging door for admission of fuel into the generator, the jet being at least sufficiently powerful to overcome the draft exerted on the carburetor and superheater by the escape of volatiles through the charging opening in the generator and that exerted by the superheater on the stack so that concurrently with the escape of volatiles evolved upon charging through the charging opening of the generator, gas present in the carburetor and superheater flows through the stack and entry of air through the stack is effectively prevented. Thus, in accordance with my invention, the operations would involve cycles each consisting of an air blasting step alternating with water gas making steps involving the passage of steam through the fuel bed, and at intervals, say, after every five or more cycles, the opening of the 55 charging door, the charging of fuel, which may be coal or coke, into the generator, and the concurrent passage of steam through the stack throughout the charging operation, and while the charging door is open, the steam pressure being sufficient to create a draft in the stack greater than the draft exerted on the carburetor by the escape of volatiles in the generator and also by the downflow superheater.

By the "starting-up period" as used in the 60 specification and claims is meant the period commencing with a cold set, one in which the temperature in the superheater is at atmospheric or room temperature, or at a substantially higher temperature due to long standby period in which no gas has been made, which temperature may be below 1,000° F., and terminating when the set has been operated and until the temperature at the top of the superheater is from 1250° to 1300° F. and at the bottom of the superheater is from 65 1,000° to 1100° F. For a standard water gas set having a generator, the internal diameter of which is 10 feet and completely enclosed in a building or other housing maintained at or about 70° F., the period required for starting up a set 70

may be about 2 hours for a set at atmospheric temperature or 30 minutes for a set in standby condition. In the case of a set in which the superheater is not housed within a building so that it is subjected to atmospheric influence, the starting-up period will obviously be much longer.

The process of this invention will be more fully described in connection with the accompanying drawing, which discloses a preferred embodiment 10 of a water gas set in which the process may be carried out.

Referring to the drawing wherein like reference numerals indicate like parts, there is shown a water gas set comprising a generator 1, carburetor 2, and superheater 3. The carburetor is elevated so that its base is substantially in the same horizontal plane with the outlet 4 of the generator and this outlet communicates with the inlet 5 to the carburetor by a refractory lined 15 passageway 6. Generator 1 is equipped with the usual grate 7 for supporting a bed of fuel such as coal or coke and a fuel charging opening 8 adapted to be closed by a suitable closure 9' and is equipped with air inlets 9, 11 disposed beneath 20 the grate and above the top of the fuel bed respectively. The generator 1 has a steam inlet 12 disposed beneath the grate for supplying steam thereto. An oil spray 13 leads into the top of the generator above the fuel bed to supply oil, which 25 may be heavy oil such as Bunker C oil, during the gas making step, if desired.

The carburetor 2 rests on a suitable structural steel support 14 and may be provided at its base with two or more layers of refractory material 30 15 such as checkerbrick disposed on arches 16 positioned at the bottom of the carburetor. The portion of the carburetor above the oil spray is unobstructed throughout its horizontal cross sectional area. A water cooled oil spray 17 is located at the top of the carburetor, preferably on 35 the vertical axis thereof and is arranged to supply oil, which may be gas oil or heavy oil such as residuum or Bunker C oil, to the carburetor during the water gas making steps in a direction countercurrent to the upward flow of water gas 40 through the carburetor. A header 18 provided with downwardly directed pipes 19 is arranged to supply secondary air to the base portion of the carburetor. The top of the carburetor has a gas outlet 21 leading into the top of the superheater 3.

Checkerbrick 23, which may be of the type disclosed and claimed in United States Patent No. 1,927,834 granted September 26, 1933, completely fills the superheater 3 and rests on arches 24 disposed at the base of the superheater. Gas outlet 25 of the superheater leads into a vertical refractory lined stack 26 provided at its top with stack valve 27; the stack valve may be opened 45 and closed by any suitable means such as a hydraulic cylinder (not shown) connected thereto by link 27'. The stack preferably is of a height somewhat greater than the height of the superheater so that, as shown in the drawing, stack valve 27 is disposed above the top of the superheater and constitutes the highest point of the set.

A conduit 28 leads from a point near the top of the stack 26 into a valve casing 29, which in 50 turn communicates by pipe 31 with a wash box 32. Backrun line or conduit 33 leads from the base of the generator beneath the grate into valve casing 29. The valve casing 29, as well known in this art, is provided with a three-way 55 valve for reversing flow through the set, i. e. in

one position it permits flow of uprun gas from the superheater into the wash box 32 while closing the backrun pipe 33 and when reversed opens backrun line 33 so as to permit flow of backrun gas therethrough into the wash box while closing 5 conduit 28. A gas offtake 34 leads from the wash box to the usual purification equipment. Backrun steam inlet 35 is provided for supplying steam through the top of the stack which, as above indicated, communicates with the superheater. The various valves of the set may be operated manually or automatically in any desired manner to carry out the steps of the water gas cycle, e. g. the valves may be operated by hydraulic cylinders controlled from a control nest 13 as well known in this art.

In accordance with the invention, I provide a steam injector 37 extending upwardly into the stack adjacent the upper end thereof and communicating through pipe 38 with a suitable steam supply, e. g. a steam boiler. The injector is equipped with valve 39 having an operating member 40 connected by pivoted link 41 to the stack valve so that opening and closing the stack valve results in simultaneous opening and closing of 25 the injector valve. Steam pipe 38 is provided with manually operated valve 38' to shut off the supply of steam to the injector when it is desired to open the stack valve without permitting steam to flow through the injector.

The process of this invention may be carried out in the apparatus herein described as follows: In starting up the cold set which may be at room temperature the fuel is first introduced into the generator. After combustion of a portion of the 35 fuel in the generator so that the fuel bed is heated to a temperature of 1200° F. air is passed through the fuel bed and the resultant blast gases passed up through the carburetor, secondary air admitted through 19 and the mixture 40 burned as it flows up through the carburetor and down through the superheater, the blast gases passing through the stack valve 27 which is open into the atmosphere. This blasting step may be about fifteen minutes duration.

After the blasting step steam is introduced into the bottom of the generator, passed up therethrough, the water gas leaving the fuel bed, passing upwardly through the carburetor in contact with, or in the absence of atomized oil introduced through spray 17 and thence downwardly through the superheater and upwardly through the stack 26 from which it may pass through connection 28 to wash box 32. This step may be of about two minutes' duration.

The uprun may be followed by a backrun during which steam is introduced into the stack through steam inlet 35 and is preheated as it flows through the stack, superheater and carburetor, backrun water gas being withdrawn from 55 the base of the generator through backrun pipe 33. The backrun step may be of about one-half minute duration for the first few cycles.

The blast, uprun and backrun, with the usual purges, constitute a complete cycle. After about 60 five or more cycles the fuel bed may be replenished or, if desired, the fuel bed may be replenished more or less often. During the addition of fuel, in accordance with this invention, the stack valve is open and steam admitted through 39 at a pressure sufficient to create a draft which exceeds the draft exerted by the superheater and the escape of volatiles through the charging opening 8 so as to prevent the entry of air through stack valve 27.

The temperature in the superheater gradually rises during each succeeding cycle of the process. When the temperature at the top of the superheater reaches about 1300° F. and at the bottom 5 of the superheater about 1100° F., i. e. when the end of the starting-up period has been reached, it will generally not be necessary to continue the introduction of steam in the stack during the charging periods. Valve 39' in the steam line 38 10 may then be closed so that on continued operation of stack valve 27 valve 39 is operated by levers 40, 41, but no steam enters the stack because of the closing of valve 39'.

Since changes may be made without departing 15 from the scope of the invention, it is intended that the above description should be interpreted in an illustrative and not in a limiting sense.

I claim:

1. In the process of operating a carburetted 20 water gas set involving a generator containing a bed of fuel, which is replenished from time to time through a charging inlet located at the top of the generator, a carburetor and superheater connected in series, the top of the generator communicating with the base of the carburetor and the top of the carburetor communicating with the top of the superheater, so that flow takes place up through the carburetor and down through the superheater, and a stack connected 25 with the bottom of the superheater for flow therethrough, which process comprises repeated cycles, each cycle involving the step of blasting the fuel bed with air and burning the blast gases in the carburetor and superheater, alternating 30 with the step of making water gas by passing steam through the fuel bed and passing the resultant water gas through the carburetor and superheater, the improvement which comprises at intervals between successive cycles of steps 35 40 during the starting-up period of operation of the set, charging the fuel bed with fuel, and concurrently with the introduction of fuel into the generator, placing the stack in communication with the atmosphere and introducing a jet of gas upwardly into the stack during the charging of the generator.

2. In the process of operating a carburetted 45 water gas set involving a generator containing a bed of fuel, which is replenished from time to time through a charging inlet located at the top of the generator, a carburetor and superheater connected in series, the top of the generator communicating with the base of the carburetor and the top of the carburetor communicating 50 with the top of the superheater, so that flow takes place up through the carburetor and down through the superheater, and a stack connected with the bottom of the superheater for flow therethrough, which process comprises repeated 55 cycles, each cycle involving the step of blasting the fuel bed with air and burning the blast gases in the carburetor and superheater, alternating with the step of making water gas by passing steam through the fuel bed and passing the resultant water gas through the carburetor and superheater, the improvement which comprises at intervals between successive cycles of steps 60 65 charging the fuel bed with fuel, and concurrently with the introduction of fuel into the

generator, placing the stack in communication with the atmosphere and introducing a jet of steam upwardly in the stack to create an upwardly draft in the stack which draft more than counterbalances the draft caused by the escape 5 of volatiles in the generator, thereby preventing entry of air into the set through the stack during the charging of the fuel into the generator, and continuing the aforesaid introduction of steam into the stack during the charging periods 10 until the temperature at the top of the superheater is from 1200° to 1300° F. and at the bottom of the superheater is from 1000° to 1100° F., and thereafter during repeated cycles discontinuing the introduction of steam into the stack during 15 the charging periods.

3. In a process of manufacturing carburetted water gas in a water gas set involving a generator containing a bed of incandescent fuel adapted to be replenished from time to time through a 20 charging inlet located at the top of the generator, a carburetor and a downflow superheater connected for flow therethrough of water gas and blast gases from said generator up through the carburetor and down through the superheater 25 and a stack connected to said superheater and having a closure adapted to be opened while said generator fuel bed is being replenished, the improvement which comprises introducing a jet of gas upwardly into said stack while replenishing 30 said generator fuel bed thereby preventing gases rising in the generator creating backdraft in and drawing air into said set and forming explosive mixtures therein.

4. In a process of manufacturing water gas in 35 a set involving a generator containing a bed of incandescent fuel adapted to be replenished from time to time through a charging inlet located at the top of the generator, a downflow superheater connected for flow therethrough of water gas and blast gases from said generator down through said superheater and a stack connected to said superheater, the improvement which comprises introducing a jet of gas upwardly into said stack while replenishing said generator fuel bed, thereby preventing gases rising in the generator from 40 drawing air into said stack and forming explosive mixtures in said set.

5. In a process of manufacturing carburetted water gas in a water gas set involving a generator containing a bed of incandescent fuel adapted to be replenished from time to time through a charging inlet located at the top of the generator, a carburetor, a superheater and a stack connected in series for flow therethrough of gases from said generator up through the carburetor, down through the superheater, and up through the stack, the improvement which comprises introducing a jet of steam upwardly into the stack 55 gases when replenishing said generator fuel bed while the temperature of said stack gases is not high enough to impart sufficient buoyancy to the gases therein to counteract the tendency of the generator gases rising through the fuel charging inlet to create back draft in the set, thereby preventing air from being drawn into said stack 60 and forming explosive mixtures in said set.
